DESIGN FOR A COMBINED BOTTLE AND DISPLAY HOLDER THEREFOR

Max Schwartz, New York, N. Y.

Application September 23, 1938, Serial No. 80,051

Term of patent 3½ years

To all whom it may concern:

Be it known that I, Max Schwartz, a citizen of the United States of America, residing in New York city, in the Borough of Manhattan, county and State of New York, have invented a new, original, and ornamental Design for a Combined Bottle and Display Holder Therefor, of which the following is a specification, reference being had to the accompanying drawing, forming part thereof, wherein

Figure 1 is an elevational view of a combined bottle and display holder therefor showing my

new design, the box being lifted in order to illustrate the display stand, and,

Figure 2 is a perspective view of the combined bottle and display holder therefor in its closed position.

Figure 3 is a top plan view of the display holder shown in Figure 1.

I claim:

The ornamental design for a combined bottle and display holder therefor, substantially as shown, and described.

MAX SCHWARTZ.
